ART OF COATING SHEET MATERIAL

Edward C. Homan, East Orange, N. J., assignor
to Irvington Varnish & Insulator Co., Irving-
ton, N. J., a corporation of New Jersey

Application October 11, 1940, Serial No. 360,712

4 Claims. (Cl. 91--32)

This invention relates to the art of coating sheet material; and the invention has reference, more particularly, to means for simultaneously applying single, uniform coats of viscous liquid substance to opposite faces of moving sheet material; which coats may be either heavy or light, that is of any desired thickness within reasonable limits.

Pursuant to heretofore known methods of applying viscous liquid coatings to sheet material, it has been the practice to deposit the applied coats to one or both faces of the material by means of blunt knife-like elements or doctor blades, against which the sheet material is moved while under considerable tension. By such methods however only light or thin coats can be applied, since the required strong tensional contact of the sheet material with knife or doctor blade edges precluded deposit of a single heavy or thick coat. A heavy or thick coating could therefore only be obtained by building up, one upon another, successively applied thin coats; and such application of successive coats rendered extremely difficult, if not altogether impossible, attainment of a comparatively thick coating which would be uniform throughout its extent.

Having the defects of the above mentioned old coating methods in view, it is an object of this invention to provide a method and means for applying coats of viscous liquid substances to both sides or faces of moving sheet material, whereby the applied coatings may be of desired selected uniform thickness throughout, and wherein the coating substance when applied to textile sheet material or cloth, especially one of more or less open weave, will be uniformly concentric to the threads thereof.

The invention has for a further object to provide means for applying coatings of viscous liquid substance to opposite faces of a moving length of sheet material, such e. g. as paper, cloth, or the like, including a pair of opposed coating bars, usually of circular cross-section, between which the sheet material, bearing a dip deposited application of the coating substance, is passed; said coating bars being spaced apart at a predetermined distance to provide an intermediate orifice through which the coating substance is caused to pass with the sheet material moving therethrough, whereby coatings of uniform thickness, determined by said spacing of the coating bars, are forced or impressed upon the opposite faces of the material in a single operation.

Another object of the invention is to provide substantially simultaneously operative opposed

and spaced coating bars which are additionally relatively disposed in a calculated vertically offset relation, whereby while the coating thickness is still controlled by the lateral spacing of the coating bars, the very slight vertical offset of the latter will eliminate occurrence of horizontal or transverse waves in the moving sheet material which, if permitted to occur, would result in irregularity in weight and thickness of the applied coating substance, and would consequently produce non-uniform coatings.

Another object of the invention is to provide coating bars which are relatively flexible, in combination with rigid supporting or backing means therefor, including means whereby said coating bars may be locally relatively adjusted at desired points along the lengths thereof, to assure accurate and uniform orifice forming spacing thereof throughout their length, all to the end that equal pressure is simultaneously exerted by the bars upon the coating substance and the moving sheet material, thereby to assure an established equilibrium in oppositely applied pressure thereof upon the coating substance and sheet material which governs uniformity of the respective applied coatings, and deposit thereof concentric to the threads of cloth material, when the sheet material operated upon is of such character.

Other objects of this invention, not at this time more particularly enumerated, will be understood from the following detailed description thereof.

An illustrative embodiment of this invention is shown in the accompanying drawings, in which:

Fig. 1 is a side elevational view of apparatus according to this invention adapted to carry out coating operations under the principles thereof; Fig. 2 is a plan view of the same; Fig. 3 is a transverse vertical section, taken on line 3--3 in Fig. 2, but drawn on an enlarged scale; and Fig. 4 is a diagrammatic view showing the vertical offset relation of the coating bars of the apparatus.

Similar characters of reference are employed in the above described views, to indicate corresponding parts.

One form of apparatus, suitable to perform the method of coating sheet material according to this invention, as shown in the accompanying drawings, comprises, a supporting frame-work 10, in connection with which is supported, to extend transversely from side to side thereof, a suitably shaped dipping reservoir or tank 11 to contain a supply of the selected viscous liquid substance S with which the faces of running lengths 55 of sheet material M are desired to be coated.

Rotatably mounted within said reservoir or tank 11, and disposed so as to be submerged in the content of the coating substance S contained therein, is a dipping roll or drum 12 over which runs the sheet material M to be coated, whereby said material is passed through the coating substance so as to pick up thick layers 1 and 1' of the latter upon its opposite faces, to be carried upwardly therewith by the emerging rising course of said material M.

Suitable means are provided for conducting the sheet material M from a supply roll 13 thereof to and into said dipping reservoir or tank 11. This means is subject to wide variation in the form, arrangement and relations of its detail agencies. Illustrative thereof, the same, as shown, comprises bearing bracket means 14 for supporting the shaft or spindle 15 upon which said supply roll 13 is rotatably mounted; said bearing bracket means 14 being secured to and so as to project from an end of the framework 16 opposite to that adjacent to which said dipping reservoir or tank 11 is located. Suitably, and preferably adjustably, mounted across the end of said framework 16 adjacent to the supply roll 13 is a guide roller 16 over which the sheet material M is led from the supply roll to tensioning rollers from whence it passes downwardly into the dipping reservoir or tank 11 and around the dipping roll or drum 12 which is submerged within the content of the latter. Said tensioning rollers comprise a rearward roller 17 and a forward roller 18, the respective shafts 19 and 20 of which are journaled in suitable bearing supports 21 carried by standard brackets 22 which are affixed to and which rise from the sides of the framework 16. The tensioning rollers are so relatively disposed that the forward roller 18 is somewhat elevated above the rearward roller 17, so that the sheet material M passes beneath the latter and thence upwardly to and over the former. Said forward roller 18 overhangs the open top of the dipping reservoir or tank 11, so that the sheet material M extends therefrom downwardly into the interior of the latter to and around the dipping roll or drum 12, and so as to be submerged in and moved through the coating substance S contained in said dipping reservoir or tank 11. In order to prevent wrinkling of the sheet material M and to spread the same smoothly for passage over the tensioning rollers 17-18 and thence through the dipping reservoir or tank 11 in such smoothly spread, unwrinkled condition, a transversely curved spreader bar 23 is provided in spaced relation to and in advance of said tensioning rollers 17-18. Said spreader bar is supported by bearings 24 carried by vertical standards 25 which are affixed to and which rise from the sides of the framework 16.

Disposed above the open top of the dipping reservoir or tank 11 is the means for applying the single, uniform coatings of the coating substance S simultaneously to the opposite faces of the sheet material M which issues from said dipping reservoir or tank 11; the same comprising a pair of opposed coating bars 30 and 31, together with novel means for operatively supporting and adjusting the same in spaced relation to provide the intermediate orifice or gap through which the preliminarily coated sheet material M passes upon emerging from said dipping reservoir or tank 11.

Each coating bar is of a length exceeding the width of the material M to be coated, and each comprises a comparatively flexible and light

weight body of metal or other suitable material which is preferably but not necessarily of circular cross-sectional shape. The external surfaces of the coating bars are given a smooth and preferably highly polished finish. Each coating bar is supported by a strong rigid carrier member 32 disposed parallel to and behind the same. Each coating bar is provided with a plurality of rearwardly extending rigid coupling studs 33, which are longitudinally spaced apart along the length thereof. The free end portions of the coupling studs 33 of each coating bar extend slidably through the body of the carrier member 32 which is associated therewith for the support thereof, and mounted on said studs 33, intermediate said coating bar from which they extend and the associated supporting carrier member, are spacer collars 34 which desirably offset the former from the latter. The free end portions of said coupling studs 33 are screw-threaded for the reception of fastening nuts 35 whereby the elements of the assembly are secured together in operative assembled relation.

One of the coating bars, as 30, together with its carrier member 32 is immovably supported by standards 36 which are affixed to and rise from the sides of the framework 16, and to which the ends of said carrier member 32 are in turn affixed. The other coating bar, as 31, together with its carrier member 32 is movably supported for yieldable movement relative to the stationary coating bar 30, whereby splices connecting joined lengths of sheet material M may pass between the coating bars without straining the same or disturbing their adjusted operative spaced relation. To this end upstanding carrier arms 37 are pivotally mounted or fulcrumed on the sides of the framework 16, to the upper free ends of which the ends of the carrier member 32 associated with said coating bar 31 are affixed. Means are provided for yieldably urging said coating bar 31 toward the coating bar 30 so as to normally retain the former in its adjusted operative spaced relation to the latter. In one illustrative form of this means, as shown in the accompanying drawings, the carrier arms 37 are swung to urge the coating bar 31 toward the coating bar 30 by gravitation of weights 38 which are attached to the carrier arms by cables 39. Said cables run over pulleys 40 mounted on bearing brackets 41 affixed to the framework 16, whereby said weights 38 are suspended subject to operative gravitation.

Adjustable means are provided for primarily predetermining the opposed operative spaced relation of said coating bars 30 and 31. An illustrative form of this means, as shown in the accompanying drawings, comprises, opposed cooperating stop lugs 42 with which opposed ends of the carrier members 32 are provided, and which, by abutment one upon the other, arrest the carrier members and their coating bars in position necessary to determine the desired operative spaced relation of the latter. So that such spaced relation may be varied according to the thickness of coatings desired to be applied by the coating bars to the sheet material M moving therebetween, one of each pair of opposed stop lugs 42 is provided with a longitudinally adjustable stop stud 43 which is threaded thereinto for endwise projection therefrom and for engagement by the opposed stop lug.

The spacer collars 34 roughly predetermine the alignment of the opposed coating bars 30 and 31 as supported by their carrier members 32. Said coating bars being relatively flexible as com-

pared with their heavy and rigid carrier members 32, a more precise and very delicately adjustable alignment of the coating bars at local points throughout the lengths thereof may be attained by inserting shims 44 at desired points between the spacer collars 34 and the carrier members 32, thus not only relatively adjusting the coating bars to assure uniform desired spacing thereof at all points throughout their lengths, but also permitting micrometric adjustment of any given local area of a coating bar without displacing or disturbing the adjustment thereof at any other area or section thereof.

The relative setting of the coating bars 30 and 31 by the supporting means thereof is so effected that a carefully calculated vertical offset of one relative to the other is provided when they occupy their cooperative laterally spaced apart positions. In the coating method of this invention, the thickness or weight of the coatings is determined not by the tension of the material M but by the spacing of the coating bars themselves. It has been noticed, however, that horizontal or transverse wave or waves in the material M is likely to occur, especially when the material is of soft finished cloth, such wave or waves causing heavy pick-up of coating substance S on one or the other side of the goods, resulting in applied coatings which are not concentric to the threads of the cloth, especially of cloth of more or less open or porous weave. For example, settings of the coating bars are usually of the order of twenty-five one-thousandths of an inch apart, whereas the goods may be from four to eight one-thousandths of an inch in thickness. It will therefore be obvious that, even at such closely spaced adjustment of the coating bars, there is plenty of room for horizontal or transverse waves to occur. These waves are naturally not uniform or recurrent, and may consequently occur at any point or area of the goods to the great impairment of coating uniformity. To avoid such detrimental conditions, one coating bar (e. g. the coating bar 30) is positioned slightly above the other (e. g. the coating bar 31), see Fig. 4. The amount of this slight offset is so calculated that a vertical line A—A forms a common tangent to the opposed sides of the coating bars 30—31 when the bars are spaced apart for the distance C. For example, assuming the coating-bars 30—31 are $1\frac{1}{2}$ inches in diameter, and the relative spacing thereof at C is .025 of an inch, the vertical offset D may be readily calculated as approximately $\frac{1}{4}$ of an inch. Some variation from the theory as thus exemplified is, of course, permissible. It will be obvious that, with the coating bars thus arranged, the thickness of the coats c and c' (see Fig. 3) will still be governed by the lateral spacing C of the coating bars; the slight offset relation of the latter, which approximates a distance equal to the thickness of the material M, will permit a corresponding offset or jog in the path of travel of the material M which is sufficient to effect a slight tensioning of goods, at the point of passage thereof between the coating bars, whereby all horizontal or transverse waving is eliminated with consequent avoidance of any local irregularities in the thickness and weight of the applied coats c and c'.

It will be understood that the travel or movement of the material M from the supply roll 13 to and through the dipping reservoir or tank 11 and thence upwardly for passage between the coating bars 30—31 may be produced in any suit-

able manner. Ordinarily after leaving the coating bars, the coated material will be caused to run through suitable drying apparatus and any other treating means required or desired, and thereafter wound or rolled up as finished coated material.

In operation, the material M as it passes through the dipping reservoir or tank 11 will pick up on its opposite faces comparatively thick layers 1—1' of the coating substance S. As the material M with the thus deposited heavy layers 1—1' of coating substance S passes between the coating bars 30—31, equal pressure will be exerted simultaneously on opposite sides of the moving material M which floats, so to speak, in equilibrium between the layers 1—1' which are thinned down and gauged to produce the required single coatings c—c' of desired uniform thickness and weight, while at the same time the equilibrium thus established assures that the coatings will lie concentric to the threads of more or less open weave or porous cloth in cases where the material M is of such character. The equalized pressure exerted by the opposed coating bars is exercised in accord with known physical laws of component forces. Due to the predetermined orifice or gap between the coating bars 30—31 through which the coating substance S is caused to pass with the material M, said coating substance S is forced by the pressure induced by the traveling movement of the material M to simultaneously form, in one operation, upon opposite faces of said material, uniform single coatings c—c' which are substantially mathematically exact in quantity.

Owing to the yieldably supported condition of the coating bar 31 relative to the stationary coating bar 30, should a thickened part of the material M, such e. g. as would be produced by a splice joining lengths thereof into a continuous run, pass between the coating bars, said coating bar 31 would readily yield to its passage and then quickly return to its normal relation to the coating bar 30 without risk of undue stress or strain being applied to said coating bars or disturbance of the carefully adjusted alignment thereof.

It will be understood that various changes could be made in the above described constructions, and that widely different embodiments of this invention could be made without departing from the scope thereof as defined in the following claims. It is therefore intended that all matter contained in the foregoing description or shown in the accompanying drawings shall be interpreted as illustrative and not in a limiting sense.

I claim:

1. In apparatus for the purposes described, means to apply preliminary facing layers of coating substance to opposite faces of material operated upon, a pair of laterally opposed coating bars of circular cross-section spaced apart to provide an intermediate orifice of predetermined width through which the thus charged material is passed whereby to determine the thickness of finished coats applied thereto, rigid carrier members for each coating bar, each coating bar being comparatively flexible, means to adjustably secure each flexible coating bar to its rigid carrier member including means to flexionally adjust the same for parallel alignment with the cooperating opposed coating bar, and cooperative means connected with said rigid car-

rier members for predetermining the operative spaced relation of said coating bars.

2. Apparatus as defined in claim 1, including means for fixing one carrier member and its coating bar in stationary position, and means for movably supporting the other carrier member and its coating bar including means to yieldably hold the same in operative stopped spaced relation to said fixed carrier member and its coating bar.

3. In apparatus for the purposes described, means to apply preliminary facing layers of coating substance to opposite faces of material operated upon, a pair of laterally opposed but relatively somewhat vertically offset coating bars of circular cross-section spaced apart to provide an intermediate orifice of predetermined width through which the thus charged material is passed whereby to determine the thickness of finished coats applied thereto, rigid carrier mem-

bers for each coating bar, each coating bar being comparatively flexible, means to adjustably secure each flexible coating bar to its rigid carrier member including means spaced along the same to flexionally adjust the bar for parallel alignment with the cooperating opposed coating bar, and opposed cooperative means connected with the respective ends of said rigid carrier members for predetermining the operative spaced relation of said coating bars.

4. Apparatus as defined in claim 3, including means for fixing one carrier member and its coating bar in stationary position, and means for movably supporting the other carrier member and its coating bar including means to yieldably hold the same in operative stopped spaced relation to said fixed carrier member and its coating bar.
